COMBINATION WARNING SIGNAL AND
TROUBLE LAMP

Earl E. Franz, Canton, Ohio

Application May 8, 1952, Serial No. 286,670

4 Claims. (Cl. 177—329)

1

The invention relates to electric lights and more particularly to a transportable electric lantern having a flexible cord for connection to an automobile ignition circuit.

An object of the invention is to provide such a lantern which may optionally be used to throw a beam of light in any desired direction as manually manipulated, and which simultaneously provides a diffused red light around the lantern.

Another object is to provide a lantern of the type referred to having lighting facilities in one of its end walls, the entire casing of the lantern being formed of a transparent or translucent colored material having a light bulb therein for producing a diffused colored light.

A further object is to provide such a lantern having a bail pivotally secured thereon for the purpose of manually carrying the lantern, or for providing a stand or supporting base for the lantern.

A still further object is to provide a lantern having means for throwing a beam of white light and means for providing a red light flasher or winker, for use by motorists during the changing of tires or the making of repairs while on a highway, to warn traffic of such stop for repairs and thus eliminate accidents caused by vehicles stalled on a highway.

Another object of the invention is to provide a simple and easily assembled construction of lantern including a cylindrical shell of translucent colored material open at one end, a cup-shaped reflector being inserted into the open end of the shell and having light bulb sockets attached thereto for supporting a light bulb within the reflector and a second light bulb within the shell, a switch being carried by the reflector for controlling the circuit to the light bulb.

A further object is to provide such a lantern in which the shell is provided with a longitudinal slot at its open end, a grooved panel being connected to the reflector and insertable within said slot.

The above objects together with others which will be apparent from the drawing and following description, or which may be later referred to, may be attained by constructing the improved lantern in the manner hereinafter described in detail and illustrated in the accompanying drawing, in which:

Fig. 1 is a side elevation of a lantern embodying the invention, showing the adjustable bail positioned to serve as a stand or supporting base for the lantern, and showing in dotted lines the manner in which the bail may be adjusted to provide a handle for carrying the lantern;

Fig. 2 a fragmentary, longitudinal, sectional view through the lantern, showing the manner in which the detachable reflector carrying the light

2

bulb sockets and other parts is inserted into the open end of the shell;

Fig. 3 a detached side elevation of the removable reflector with sockets and light bulbs, flasher and switch carried thereby; and,

Fig. 4 a fragmentary, sectional view taken as on the line 4—4, Fig. 1.

The improved lantern to which the invention relates comprises a cylindrical shell 10, formed of a red translucent or transparent material such as plastic or the like, having one end open as shown at 11, the opposite closed end being preferably of semi-spherical shape as indicated at 12.

For the purpose of providing means for optionally manually carrying the lantern or supporting it upon a road or the like, a bail 13 is provided, having opposite ends thereof pivotally connected to opposite sides of the shell 10, at points spaced from the closed end thereof, as indicated at 14. 20 This bail is of angular shape having the shorter legs 15 and the longer U-shape portion 16.

At the pivotal points of the bail, bosses 17 may be formed upon the sides of the shell 10, having angularly disposed grooves 18 and 19 therein for 25 engaging the shorter legs 15 of the bail for holding them in the full line position shown in Fig. 1, to form a stand or supporting base for the lantern, or in the dotted line position to provide a handle for manually carrying the lantern.

30 A detachable sheet metal cup-shaped reflector 20 is provided, of suitable size to be inserted into the open end 11 of the shell 10 and having the peripheral flange 21 adapted to be engaged over said open end of the shell.

35 This reflector may be of any suitable cup-shape, preferably being tapered inwardly from its outer end for a distance, as indicated at 22, and then tapered at a greater angle, as at 23, having the flat inner wall 24.

40 An important feature of the invention is the assembling of the light bulbs in their sockets, flasher if desired, switch, circuit wires and flexible connector cord upon the reflector, so that they may be all removed from the shell as a unit with the reflector.

45 An angular ring 25 is provided for engaging over the end of the reflector and the open end portion of the shell for holding the reflector in assembled position upon the shell, as best shown in Fig. 2.

50 A bracket 26 is attached to the flat inner wall 24 of the reflector, as by bolts 27 or the like, and has mounted thereon sockets for receiving the light bulb 28, located within the reflector, and the light bulb 29, located within the shell 10.

55 The socket for the bulb 28 comprises the spring clip 30, for engaging the base 31 of the bulb 28, and the terminal 32 for contact with the terminal end 33 of the bulb. In like manner the socket for the light bulb 29 comprises the spring clip 34, for

engaging the base 35 of the bulb, and the terminal 36 for contacting the terminal end 37 of the bulb.

A flasher, indicated generally at 38, may be provided in the circuit to the light bulb 29 and is supported upon the reflector assembly by the rigid conductor wire 39, connected to the bracket 26 as by one of the bolts 27, and by the rigid conductor wire 40 connected to the terminal 36.

A switch, indicated generally at 41, is located in the circuit and adapted to be manually operated, as by the switch button 42. This switch is connected by a wire 43 with the terminal 32 and by wire 44 with the flasher 38.

A wire 45, leading from the switch, and a wire 46, leading from the bracket 26, join to form the flexible cord 47 upon the end of which may be located any conventional type of connector plug 48 adapted to be inserted into the socket of a cigarette lighter in the instrument panel of an automobile.

In order to support the switch 41 upon the reflector 20 a grooved strip 49, which may be formed of plastic or other suitable material, is rigidly connected to one side of the reflector, as by the rivet 50 located through the reduced end 51 of the strip 49 and through the adjacent portion of the reflector. The switch 41 is rigidly mounted upon this grooved strip 49.

The strip 49 is preferably rounded at its inner end, as at 52, and a continuous groove 53 extends along the upper edge, rounded inner end and the lower edge of the strip 49. A slot 54, of suitable size to receive the grooved strip 49, is formed at the open end of the shell 10 and the strip 49 is slidably received in this slot.

For the purpose of permitting cooling air to pass through the shell 10, louvers 55 may be formed in opposite sides thereof, so that air continuously passing through the shell will prevent overheating of the shell from the bulb 29.

With this construction it will be seen that both light bulbs, with the entire circuit therefor, including the flasher and switch, are carried as an assembly upon the reflector 20 so as to be removed as a unit from the shell 10.

From the above it will be apparent that a simple, inexpensive and efficient lantern is provided which may be manually manipulated to direct a beam of light from the light bulb 28 onto a tire, or other portion of an automobile being repaired, while the bulb 29 within the translucent shell 10 will provide a diffused red warning light which may intermittently flash or wink if desired.

It will also be seen that the bail may be easily and quickly adjusted to form either a handle for manually manipulating the lantern or a stand or base support for supporting the lantern on a roadway or the like for providing a warning light.

In the foregoing description, certain terms have been used for brevity, clearness and understanding, but no unnecessary limitations are to be implied therefrom beyond the requirements of the prior art, because such words are used for descriptive purposes herein and are intended to be broadly construed.

Moreover, the embodiments of the improved construction illustrated and described herein are by way of example, and the scope of the present invention is not limited to the exact details of construction.

Having now described the invention or discovery, the construction, the operation, and use of preferred embodiments thereof, and the advan-

tageous new and useful results obtained thereby; the new and useful constructions, and reasonable mechanical equivalents thereof obvious to those skilled in the art, are set forth in the appended claims.

I claim:

1. A safety lantern comprising a translucent colored shell open at one end, a cup-shaped reflector means detachably mounting the reflector within the open end of the shell, a light bulb within the reflector, a socket for said light bulb mounted upon the exterior of the reflector, there being an opening in the reflector to receive the base of the light bulb, a second socket mounted

15 upon the exterior of the reflector and a light bulb located in said second socket upon the exterior of the reflector and within the shell.

2. A safety lantern comprising a translucent colored shell open at one end, a cup-shaped reflector means detachably mounting the reflector within the open end of the shell, a light bulb within the reflector, a socket for said light bulb mounted upon the exterior of the reflector, there being an opening in the reflector to receive the base of the light bulb, a second socket mounted

20 upon the exterior of the reflector and a light bulb located in said second socket upon the exterior of the reflector and within the shell, a circuit to said light bulbs and a switch in the circuit and mounted upon the reflector.

25 3. A safety lantern comprising a translucent colored shell open at one end, a cup-shaped reflector means detachably mounting the reflector within the open end of the shell, a light bulb within the reflector, a socket for said light bulb mounted upon the exterior of the reflector, there being an opening in the reflector to receive the base of the light bulb, a second socket mounted

30 upon the exterior of the reflector and a light bulb located in said second socket upon the exterior of the reflector and within the shell, a circuit to said light bulbs and a switch in the circuit and mounted upon the reflector.

35 4. A safety lantern comprising a translucent colored shell open at one end, a cup-shaped reflector means detachably mounting the reflector within the open end of the shell, a light bulb within the reflector, a socket for said light bulb mounted upon the exterior of the reflector, there being an opening in the reflector to receive the base of the light bulb, a second socket mounted

40 upon the exterior of the reflector and a light bulb located in said second socket upon the exterior of the reflector and within the shell, a circuit to said light bulbs, a flasher in the circuit to the last named light bulb, and a switch in the circuit and mounted upon the reflector.

45 5. A safety lantern comprising a translucent colored shell open at one end, a cup-shaped reflector means detachably mounting the reflector within the open end of the shell, a light bulb within the reflector, a socket for said light bulb mounted upon the exterior of the reflector, there being an opening in the reflector to receive the base of the light bulb, a second socket mounted

50 upon the exterior of the reflector and a light bulb located in said second socket upon the exterior of the reflector and within the shell, a grooved panel connected to the exterior of the reflector, there being a slot in the open end of the shell to receive said grooved panel, a circuit to said light bulbs and a switch in the circuit and mounted upon said grooved panel.
